(57) **CLAIM**

The ornamental design for a battery, as shown and described.

DESCRIPTION

The design of the present application is directed to a battery that can be used, for example, in a camera or camcorder.

FIG. 1 is a top and right front perspective view of a first embodiment of a battery, showing our design;

FIG. 2 is a front elevational view of the first embodiment;

FIG. 3 is a rear elevational view of the first embodiment;

FIG. 4 is a left side elevational view of the first embodiment;

FIG. 5 is a right side elevational view of the first embodiment;
FIG. 6 is a top plan view of the first embodiment, rotated ninety degrees clockwise;

FIG. 7 is a bottom plan view of the first embodiment, rotated ninety degrees counterclockwise;

FIG. 8 is a top and right front perspective view of a second embodiment of a battery, showing our design;

FIG. 9 is a front elevational view of the second embodiment;

FIG. 10 is a rear elevational view of the second embodiment;

FIG. 11 is a left side elevational view of the second embodiment;

FIG. 12 is a right side elevational view of the second embodiment;

FIG. 13 is a top plan view of the second embodiment, rotated ninety degrees clockwise;

FIG. 14 is a bottom plan view of the second embodiment, rotated ninety degrees counterclockwise;

FIG. 15 is a top and right front perspective view of a third embodiment of a battery, showing our design;

FIG. 16 is a front elevational view of the third embodiment;

FIG. 17 is a rear elevational view of the third embodiment;

FIG. 18 is a left side elevational view of the third embodiment;

FIG. 19 is a right side elevational view of the third embodiment;

FIG. 20 is a top plan view of the third embodiment, rotated ninety degrees clockwise;

FIG. 21 is a bottom plan view of the third embodiment, rotated ninety degrees counterclockwise;

FIG. 22 is a top and right front perspective view of a fourth embodiment of a battery, showing our design;

FIG. 23 is a front elevational view of the fourth embodiment;

FIG. 24 is a rear elevational view of the fourth embodiment;

FIG. 25 is a left side elevational view of the fourth embodiment; and,

FIG. 26 is a right side elevational view of the fourth embodiment.

The phantom lines shown in the fourth embodiment are for the purpose of illustrating environmental structure and form no part of the claimed design.
